GARMENT HANGER

William H. Smith, Evanston, Ill.

Application October 1, 1951, Serial No. 249,073

4 Claims. (Cl. 223—88)

1

This invention relates to a garment hanger for different articles of apparel. More particularly it deals with such hangers especially adapted for suits of either men or women.

It is an object of this invention to provide a simple, efficient, effective and economic garment hanger for suits which will maintain the pressed form of the garments unwrinkled and smooth.

Another object is to provide a garment hanger on which may be supported coats, trousers and skirts, separately or together, including capacity for a full suit ensemble, the parts of which are supported with sufficient looseness so that they will remain ventilated, thereby avoiding stuffiness in appearance or the entrainment of obnoxious odors.

Another object is to provide a compact garment suit hanger which is convenient to use, easy to handle and to pack when out of use, and which aids in maintaining a natty dressed appearance for the one using it, and to support and transport suits in a ready-to-wear condition.

Generally speaking, the garment hanger of this invention comprises a triangular-shaped wire frame at the apex of which is a hook and along the base of which are a pair of spaced relatively horizontal and springy members having upwardly extending loops of different configurations over which the cuffs of trousers or the belt loops of trousers or skirts may be hung; one cuff being hung on one side of the hanger and the other cuff of the other leg being hung on the other side of the hanger. The resiliency or springy character of the horizontal portions maintains the width of the pant legs stretched while being suspended on the hanger.

The above mentioned and other features and objects of this invention and the manner of attaining them are given more specific disclosure in the following description of an embodiment of the invention taken in conjunction with the accompanying drawing, wherein:

Fig. 1 is a side elevation of an embodiment of the garment hanger of this invention with fragmentary showings of apparel being supported thereon;

Fig. 2 is a partial plan view of the more rigid or upper portion of the support of the hanger shown in Fig. 1;

Fig. 3 is a side elevation of the more rigid or upper portion of the support shown in Figs. 1 and 2;

Fig. 4 is a plan view of the horizontally extending portions of slightly springy character extending between the lower ends of the more rigid or

2

upper portion shown in Fig. 3, with the major part of said upper portion broken away;

Fig. 5 is a side elevation of the right half of the pair of lower or horizontally extending portions, with dotted lines to show the springy character and how the horizontally extending portions may be distorted; and

Fig. 6 is a perspective view of the hanger shown in Fig. 1 without garments being supported thereon.

The specific embodiment of this invention disclosed in the drawings comprises a lower rigid upper portion which may be made of a single piece of more rigid wire bent at its center back 15 against itself to form a two ply hook 1, and then being separated into two opposite extending sides 2 of an obtuse triangle forming the shoulders supports for a coat type garment with its outer ends being rounded at 3 and bent inwardly to form short tips or ends 4 (see Figs. 2 and 3).

The other portion of the hanger comprises two more resilient wire members normally horizontal in position which extend between the ends 4 and are spaced apart by the thickness of the wire in 25 the ends 4, being welded or soldered at 5 integral with said ends as shown in Fig. 4. These horizontal portions are symmetrical about their center and comprise from each end extending inwardly: relatively vertical loop hooks 6 which are spaced apart at least the thickness of the wire portion 4 as shown in Fig. 4, then extend relatively horizontal straight sections 7 to another type of offset and wider upstanding loops 8, such as shown in Figs. 1 and 5, having straight tops and sides sloping toward the adjacent ends 4, so as to fit into the corners of the cuffs of trousers as will be described later. The four offset loops 8 are connected together by other horizontal straight sections 9, normally in alignment with the sections 7, which sections 9 are divided at their centers by the center line 10 of the hanger assembly, so that all of the loops and portions of the resilient part of the hanger are symmetrical about the center line 10.

When the central portion 9 is shifted toward the hook portion 1 into the dotted line position 11 shown in Fig. 5, it can be seen that the lower portions of the loop hooks 6 are widened while the upper portions of the loops 8 are spread apart 50 towards the bends 3 of the hanger, thereby tensioning any trouser cuff 12 held between two adjacent loops 8 on the same horizontal resilient member, which tensioning also tensions the width of the trouser leg 13 upon which the cuff is formed (see Fig. 1). Thus, with the cuff of one leg of

the trousers being hooked over the pair of loops 8 on one side of the hanger, the inside of the cuff of the other leg of the trousers may be hooked over the other pair of loops 8 on the other side of the hanger, so that the trousers will hang loose and unwrinkled as well as being stretched in their width due to the resiliency of the horizontal wire portions 6, 7, 8 and 9.

The common hanger of the present invention is also adapted for carrying trousers and skirts in another manner, namely by their belt loops 14 around their waists, which belt loops may be slipped over the narrow vertically extending loop hooks 6 at each end on either side, or both sides, of the hanger as shown in Fig. 1. Thus, a skirt 15 which does not have cuffs but does have belt loops 14, may be supported by the hanger of this invention, as well as trousers which may be supported either by their cuffs or by their belt loops. If more than one pair of trousers is to be placed on the hanger, such can be done by hooking one pair onto the loops 8, while the other pair may be hooked by their belt loops onto the loop hooks 6.

On the same hanger, and over the skirt and/or trousers, may be hung the coat 16 with its shoulders resting upon the sloping sides 2 of the more rigid and upper support portion of the hanger as shown in Fig. 1. Thus, the skirt 15 and/or trousers 13 hang freely inside of the coat 16, all of which are loosely, neatly and smoothly supported by the single garment hanger of this invention.

While there is described above the principles of this invention in connection with specific apparatus, it is to be clearly understood that this description is made only by way of example and not as a limitation to the scope of this invention.

What is claimed is:

1. A garment hanger comprising a central suspending hook, a pair of downwardly diverging shoulder supporting portions and a pair of parallel similar cross members secured to the outer extremities of said shoulder supporting portions,

10
15

said cross members having adjacent each of their ends upwardly projecting fingers adapted for engaging belt loops of garments and the section of each cross member between said fingers having a pair of upwardly extending loops in the same plane as said fingers, said loops diverging with respect to each other and having open bottoms and aligned horizontal top sections, whereby said loops are adapted to be inserted in the cuffs of trousers, the fingers and diverging portions of one cross member being coplanar and parallel to the fingers and diverging portions of the other cross member.

2. A hanger according to claim 1 wherein said cross members are resilient.

3. A hanger according to claim 1 made of wire, said pair of parallel similar cross members being made of more resilient wire than said hook and downwardly diverging shoulder supporting portions.

4. A garment hanger comprising: a central suspending hook, a pair of downwardly diverging shoulder supporting portions, and a pair of parallel spaced similar resilient wire cross-members secured at their ends near the outer extremities of said shoulder supporting portions and at said ends closing the space between said members, each of said members having a pair of upwardly projecting inverted U-shaped loops with horizontal top sections, said loops being symmetrically spaced each side of the center of said member and being connected by a horizontal section of said member downwardly offset from said top sections, said loops being adapted to engage portions of garments thrust thereover.

WILLIAM H. SMITH.
